poration, Brooklyn, N. Y., a corporation of West
Virginia

Application December 8, 1930, Serial No. 500,902
Renewed November 12, 1935

14 Claims. (Cl. 91—45)

This invention refers to an apparatus for coating the inside of pipes, tubes, etc.

The object of the invention is to provide an apparatus for automatically and uniformly coating the inside of tubular articles, so that pipes to be coated, after having been fed either manually or mechanically to the apparatus, are automatically coated on the inside throughout their entire length, and then being automatically discharged from the apparatus.

With the foregoing and other objects in view, my invention consists of certain other novel features of construction and arrangement of parts which will be apparent from the disclosure herein and more fully described and shown by the accompanying drawings wherein:

Fig. 1 is a side elevation showing an apparatus for enameling the inside of pipes, certain of the parts being omitted for clearness.

Fig. 2 is a plan view of the same.

Fig. 3 is an end elevation view of the apparatus from the right of Fig. 1.

Fig. 4 is an end elevation view from the left of Fig. 1.

Fig. 5 is a side elevation view of the traveling carriage, propelling and locking mechanism.

Fig. 6 is a sectional view of Fig. 5 on line ZZ.

Fig. 7 is an enlarged detail side elevation view of the upper right hand corner of Fig. 5 showing a portion of the traveling carriage and pipe clamping device.

Fig. 8 is a plan view of Fig. 7.

Fig. 9 is a sectional view of Fig. 8 on line XX.

Fig. 10 is a side elevation view showing in detail and partial section the spray gun mounting, automatic safety circuit breaking device and automatically operated check valve for controlling functioning of fluid control mechanism of spray gun, and

Fig. 11 is a plan view of Fig. 10.

In the specific embodiment of the invention as shown in the drawings, and referring particularly to Figs. 1—4 inclusive, the apparatus of this invention comprises a central mechanism for supporting and coating a plurality of pipes, tubes or the like, and on each side of this central mechanism is a feeding mechanism supplying the pipes to the coating mechanism and delivering the pipes therefrom in coated condition. The direction of the feed of the pipes through the apparatus is from front to back in the direction of arrows in Fig. 2 so that the supply mechanism is in front in Figs. 1 and 2 and on the left in Fig. 3 and on the right of Fig. 4, the discharge mecha-

nism being on the opposite side of the central coating mechanism.

The frame work of the machine (Figs. 3 and 4) comprises a series of standards 180 on the entrance side and supporting members 181 on the discharge side with the upper cross members 182 and lower cross members 183 connecting across between the opposite sides of the machine. The longitudinal channel bars 32 are supported by cross pieces 182 and in turn slidably support the carrier 38 upon which is rotatably mounted the drum member 23 holding the pipes to be coated. The drum member 23 provides at each end the recesses or sockets 29 for the pipes and between said sockets extend the longitudinal trough members 176 which in section conform to the shape of the sockets 29. This drum member 23 rotates counter-clockwise (Fig. 4) to pick up the pipes from the tracks 1—2, and then moves to vertical position where it is locked against rotation while the carriage 38 reciprocates longitudinally to move the pipes held in the upper sockets of the drum lengthwise on to and over the spray nozzle extension 61, the nozzle spraying only during the return movement of the carriage 38 and drum 23.

Upon completion of the spraying the drum 23 is unlocked and again rotates counter-clockwise (Fig. 4) to deposit the sprayed pipes on the tracks 104, at the same time picking up a new load of pipes from the supply tracks 1—2. The delivered pipes P roll down along the tracks 104 and are picked up in sequence by the projections of the disks 175, which deposit them in accurately timed sequence in the sockets of a continuous discharge conveyor (not shown) running over the sprockets 173 (Fig. 2) on the same shaft 174 with the delivery disks 175 and driven by sprockets from the drive shaft 171.

The spray mechanism and controls therefor are shown at the right of Figs. 1 and 2, the spray guns 72 having the extending nozzles 61 projecting substantially horizontal towards the left and mounted at their left ends in bearings in the pedestal 36 of the reciprocating carriage 38. Intermediate their ends a removable support or bracket 64 is provided which is automatically turned downward out of the way of movement of the carriage engaging roller 63 to turn the beveled gear 177 counter-clockwise (Fig. 2) so that the beveled gear 178 will turn the supporting arm 64 down in advance of the movement of the carriage, and as the nozzle extensions 61 protrude further and further in through the sockets 55

of the pedestal 36 and into the troughs 176 or the pipes positioned in said troughs.

Fume exhaust means is provided at the left end of the machine (Figs. 1 and 2) in the form 5 of a hood member 146 supported from the pedestal 37 so as to move with the carriage 38 and sliding in the fixed tube 148 so as to provide a permanent outlet irrespective of the position of the reciprocating carriage 38.

10 The drive for the machine as shown in Figs. 1, 2, 3 and 4 comprises a prime mover 160 indicated as a pulley, but preferably an electric motor, driving the longitudinal shaft 171 upon which is the worm 161, which through worm wheel 162, shaft 163, clutch 164 and shaft 166 drives the worm 167 geared to the worm wheel 168 on shaft 169 carrying the sprockets 170 for the feed conveyor 28. When the clutch lever 165 (Fig. 3) is in position 15 to connect the teeth of clutch 164, the feed conveyor 28 is continuously driven to supply pipes to the entrance tracks 1-2. Similarly the delivery conveyor (not shown) is continuously driven from the shaft 171 and picks up the pipes as they are carried over by the projections of the discharge wheels 175, which in turn pick up the pipes 20 in sequence from the inclined discharge tracks 104.

The drive shaft 171 is extended longitudinally 25 to the worm and worm wheel combination 18, driving the transverse shaft 17 (Figs. 2 and 4), driving the gear 16 and the gear wheel 15 running freely upon the shaft 105' but adapted to be connected thereto by the clutch 13 engaging the orifice 14 of the gear so as to turn the sprockets 105 driving the endless chains 46. These chains reciprocate the carriage 38 through engagement of the roller 49 with the faces of the brackets 57 and 69, and the drive for intermittently rotating the drum 23 is also provided 30 by the movement of this chain driving the sprockets 45 (Fig. 4) to turn shaft 34, which through gearing 44' continuously rotates the gear 44 intermittently rotating the gear 42 to give intermittent rotation to the drive gear 39, fixed on 35 shaft 35 carrying the rotatable drum 23.

In Figs. 5 and 6 the drive for the carriage 38 is shown on enlarged scale together with portions 40 of the drive for the rotary drum 23 and the locking mechanism for the drum at 58, 59 and 60 to the right of Fig. 5, above which is shown in 45 section the gripping means to hold the pipes in place accurately aligned with relation to the ends of the nozzle extension 61.

Figs. 7, 8 and 9 show this gripping means for 50 the pipes P on still further enlarged scale, parts of the gripping means being omitted from these views for the sake of clearness. In general this gripping means is shown as mounted at the end 55 184 of the drum 23 fixed on the rotatable shaft 35 journaled in the pedestal 36 of the carrier 38. The gripping fingers 25, 30 pivoted as shown are 60 centered with relation to the sockets 29 and are actuated by the levers 118, 119 (Fig. 8), which in turn are operated automatically during the 65 rotation of the drum by relative longitudinal movements of the wedges 120 and 122 as herein-after explained, so that the pipes will be positioned in the sockets 29, then gripped and held therein during the coating operation, and then 70 automatically released therefrom after the coating operation is completed.

The apparatus of this invention is also provided with automatic safety mechanism shown on 75 enlarged scale in Figs. 10 and 11 so that any ex-

cess of pressure beyond a predetermined amount on any one of the nozzles 61 will automatically cause the nozzle 61 and its gun 72 and the supporting parts 138, 139 to move backward against the pressure of the spring 135 and cause the head 136 of rod 134 to tip the hinged member 141 counter-clockwise (Fig. 10) to actuate the switch 145 and immediately stop the machine. The detailed structure and operation of the apparatus 10 will now be described starting with the automatic feeding of the pipes to the holding drum 23.

Pipes to be coated inside or fed by conveyor 28 to runway formed by tracks 1 and 2 at the ends of the pipes (Fig. 4), and as the first pipe on the conveyor reaches the point where it will contact 15 with projection 3 of lever 4, it will force lever 4 out of its path.

Lever 4 is pivoted to standard 31 and connected by rod 6 to arm 7 and through the medium of shaft 8 causes lever 9 to turn counter-clockwise 20 (Fig. 4), thus breaking the straight line formed by clutch rod 11, link 10 and lever 9.

The spring 12 by pressing clutch rod 11 upward will continue the movement of the parts linked together until the long end of lever 9 is stopped 25 by coming in contact with the main frame 32.

The upward movement of clutch rod 11 releases clutch pin 13 and spring 12' forces pin 13 into recess 14 in gear 15, which meshes with gear 16 30 on shaft 17, which is driven through gear unit 18, which in turn is driven from any usual source of power.

Should the enameling unit be operated as a single unit and the pipes fed manually, the apparatus will be set in motion by manually shifting 35 lever 9, which will have the same effect as the pipe contacting with projection 3 of lever 4, as above described.

The feed timing levers 19 (Figs. 2 and 4) are actuated through ratchet gear 20 and timed so 40 as to synchronize with the delivery of pipe from conveyor 28, the chain 28 running around sprockets indicated at 28' fixed on the same shaft with gear 20. Ends 21 of levers 19 momentarily stop the pipe as it rolls down runway 1-2, and at the 45 same time straighten same, after which the pipe is released and continues down runway and contacts with end stop 22.

As drum 23 starts to rotate counter-clockwise 50 around axis of shaft 35 (Fig. 4) when the apparatus is started, extensions 24 of clamping fingers 25 at one end (Figs. 5, 6 and 9) and the corresponding projections 26 of fingers 27 at the other end engage under and pick up the pipes in sequence while passing tracks 1 and 2. The pipes 55 roll down the incline formed by projections 24 and 26 into pockets 29. After the pipe rolls down projections 24 and 26 one end of the pipe comes in contact with slanted projection 33 attached to the head bracket 36, where the pipes are shifted so 60 that end of the pipes will be in a straight line. The clamping fingers 25-30 then clamp the pipe to the drum 23 at the center of the pockets 29, as shown in Fig. 9, and described in detail here- 65 after.

The drum 23 is mounted on shaft 35 resting in bearings of end brackets 36 and 37 (Fig. 1), which in turn are attached to reciprocating carriage 38. The drum 23 makes only one half revolution at a time and is driven by means of gear 39 mounted on shaft 35 meshing with gear 40, both mounted on bracket 37, and gear 40 is provided with pilot pins 41 engaging with gear 42 by sliding into recesses 43 in gear 42, which 70

is actuated by intermittent gear 44 (Figs. 4 and 1) driven through the medium of suitable gearing 44' from sprockets 45 on shaft 34, and so timed that the drum 23 makes one half revolution while 5 the carriage 38 is in a stationary retracted position.

This timing is obtained by proportioning the length of the drive chains 46-46 of carriage 38 and the chain path in such a manner as to give 10 sufficient time for the roller 49 supported on a pin between chains 46-46 (Fig. 6) to travel idle after leaving sprockets 47-47 and until reaching sprockets 48-48 (Fig. 5). During this time the carriage 38 is stationary while the chains 46-46 15 continue their travel. The drum 23, having made one half revolution during which it is loaded with three pipes as above described, stops rotation holding the pipes in top position, and the carriage 38, on which the drum is carried, is now 20 ready to be moved toward the end where spray guns are located to thread the pipes over the ends of the guns.

The carriage is locked to the frame during rotation of drum 23 and is released by roller 49 25 of continuously moving chains 46-46 contacting with lever 50, (Fig. 5), levers 50 and 51 being both attached to shaft 52 and turned counter-clockwise by roller 49, thereby pushing locking piece 54 out of notch block 102 by means of rod 30 53, which is pivoted at 56 to lever 51.

The carriage 38 is started to move gradually from position shown in Fig. 1 while the conveyor chains 46-46 are passing over sprockets 48 by roller 49 pressing against guide surface 57' of bracket 57, which is attached to carriage 38. The speed of carriage 38 is gradually increased as conveyor chains pass around sprockets 48, and full speed obtained as it leaves the sprockets (Fig. 5). As the carriage 38 starts to move drum locking pin 58 attached to bracket 36 is forced 40 into socket 59 of the drum by compression spring 60, thus locking the drum to the carriage and preventing it from rotating during its travel from right to left and return (Fig. 1). As carriage 38 45 with drum 23 attached moves toward spray guns, nozzles 61 enter pipes which are now rigidly held. The ends of nozzle extensions 61 are guided in bearings of bracket 36, which bracket is attached to carriage 38.

50 After nozzles have entered the pipes approximately halfway, there is no further need for the center nozzle supports, the cam 62 contacts with roller 63, moving nozzle support 64 out of position, permitting carriage to proceed to the extreme right, roller 63 after leaving cam rides along frame of carriage.

Locking levers 25 are so arranged that when clamping a pipe (Fig. 9), their upper outline 24 60 bears a definite relation to the center line of the nozzles, thereby automatically turning off or on the flow of coating fluid by preventing or allowing air to pass to fluid control chamber of the spray gun. When there is a pipe in socket 29 and held in position by clamping fingers 25-30, 65 the upper portion of clamping finger will then contact, after the carriage has made its full movement, with plunger 66 (Fig. 10) actuating air valves 67 to open the valves one for each nozzle. However, should no pipe have been picked up, and, therefore, none in one of the sockets 29, the corresponding clamping fingers will be closer together and the upper portion of locking lever 25 will pass by the corresponding plunger 66 and contact with plunger 65 and 70 actuate the valve 67 in the opposite direction,

closing it if open. Valves 67, one for each nozzle, are normally turned on when the machine is in operation, and are provided only in case no pipe is picked up at the loading end, and thereby prevent spraying the apparatus, and other pipes in position to be sprayed, should there be no pipe in one of the pockets 29. 5

The carriage 38 having travelled the full distance toward the spray nozzles, direction of travel is automatically reversed by the roller 49 attached to the chains 46 running around sprockets 68 and contacting with guide surface 69' of bracket 69 (Fig. 5) attached to carriage 38, and finally ending return travel of carriage 38 when roller 49 passes over sprockets 47 and 70 disengaging roller 49 from between surfaces 69' and 57'. 15

It is of particular importance to note the gradual speeding up of the carriage from zero to full speed and the reduction of speed from full 20 speed to zero on reversing motion of carriage, and again picking up from zero to full speed, etc.

The movement of carriage having been reversed, the ends of nozzle extensions 61 of spray guns 25 72 are now at the extreme ends of the pipes to be enameled, and the roller 73 of lever 74, which is pivoted to carriage 38 and held by means of spring 75 in a horizontal position (Fig. 1) has passed over cam 76 secured to frame and engages upon the reversing of the carriage movement between the lower surface of cam 76 and projection 77 of bell crank lever 78, which is pivoted to the frame and forces same to swing counter-clockwise. 30

Rod 79 pivoted to lever 78 and guided by brackets 80 is then pulled against spring tension of compression spring 81 until the end 82 of bell crank lever 83 snaps behind the shoulder of ring 84 and locks it and lever 78 in position. 35

The control valves 85 and 86 for the spray nozzles are connected to lever 78 and are opened and held open by the latter. 40

The atomizing air then rushes through the main valve 87, regulator 88, automatic valve 85, air pipes 89, 90, hose 91, gun 72, extension 61 45 and out of the spray nozzle end 92 (Figs. 3 and 1).

The coating fluid is brought to nozzle extensions by hose 151 supplying compressed air to spray fluid container 152, thus holding spray 50 fluid under pressure and forcing it through hose 153, strainer 154, hose 155 and into spray gun 72 and nozzle extension 61.

The coating fluid is started to flow by the air coming through valve 87, pipe 93, automatic 55 valve 86, pipe 94, automatic cutout valve 61, hose 95 and into spray gun, actuating the fluid flow control piston of spray gun 72, thereby releasing coating fluid at nozzle 92.

As the carriage continues to proceed, the nozzle 60 support 64 swings back into position through pressure of compression spring 96 supporting the nozzle extensions, and at the end of the return travel of carriage 38 the stop bracket 97 on the carriage (Figs. 1 and 2) contacts with lever 83 65 tipping it counter-clockwise and releasing connecting rod 79, thereby shutting off through movement of bell crank 78 spray fluid and atomization air through air control devices 86 and 85. 70

At this stage the drum locking device is released by projecting head 98 of locking pin 58 being held back by projection 99 of bracket 100 (Fig. 6) which pulls out locking pin 58 from socket 59. Then the pilot pins 41 (Fig. 5) engage with the 75

follower gear 43 by sliding into the recesses 43 located in this gear, which is in mesh with intermittent gear 44 and at the same time carriage is locked to frame by slanted portion 101 of the block 102 5 raising lock 54 and connected parts, which, as the carriage moves on, fall on account of their weight into notch 103, locking the carriage 38 to frame 32. Should the lock not fall in position, roller 49 after passing over sprocket 10 passes along 10 guide 69' and must pass over lever 50, pressing same to turn clock-wise and positively force lock into notch 103.

The intermittent gear drive for rotating drum 23 is so timed that when locking pin 58 has been 15 removed from the drum and carriage lock 54 is in place, the drum starts rotation to discharge the pipes previously enameled, and also picks up at the opposite side pipes to be enameled. As the drum rotates to discharge the enameled pipe, the 20 clamping fingers are opened in a manner similar to closing, and hereinafter described in detail, and tracks 104 (Fig. 4) engage the pipe to be discharged as the drum rotates and they then roll down the incline portions of the tracks.

25 In Figs. 5 and 6 is shown the complete path of the conveyor chain used for providing movement to the drum 23, carriage 38 and locking devices according to the following description, which is here repeated so the full cycle of the conveyor 30 chain may be followed.

The two chains 46 are driven continuously by sprockets 105 along a fixed path because of idle sprockets 106, 48, 68, 47, 70, 107, and the drum 35 driving sprocket 45. The chains 46 are cross-connected by pin 108 carrying roller 49. During one half revolution of the drum and one full movement of the carriage back and forth, conveyor chains 46 make one complete cycle. When the carriage has arrived at the extreme left-hand 40 position, the carriage is locked to main frame 32 by means of locking piece 54, which is guided in bracket 109 and engages into notch of block 102 of carriage 38. The carriage is unlocked before 45 being set in motion by roller 49 moving levers 50 and 51 in direction indicated by arrow (toward sprockets 48), forcing lever 50 and lever 51, both fixed on shaft 52, to turn counter-clockwise and thereby pushing locking piece 54 out of engagement with block 102 through medium of rod 53, 50 which is pivoted at 56 to lever 51. Then the roller 49 continuing along its path over sprockets 48 starts the motion of carriage 38 and accelerates it gradually to its full speed by pressing against 55 guide surface of bracket 57 secured with bracket 69 to carriage 38; thus carrying the carriage for a full movement to the right, gradually reducing the speed to zero, and then reversing the direction of travel by passing around sprockets 68 and 60 movement of carriage ending gradually while roller 49 passes over sprockets 47 and 70.

Toward the end of the travel of the carriage to the extreme left the slanted portion 101 of block 102 raises lock 54 with its component parts, which 65 then falls because of its weight into notch 103, locking the carriage 38 to frame 32. After roller 49 passes over sprocket 10 it rides down guide 69' and passes lever 50, forcing same to turn clockwise and thus positively locking carriage 70 should for any reason lock 54 have failed to fall into notch 103 because of its own weight.

Figs. 7, 8 and 9 show in detail the clamping fingers 25-30 and component and operating parts. The clamping device shown is actuated 75 by the rotation of drum 23. Roller 110 attached

to plunger 111 contacts with cam 112 and rides up incline 113, actuating plunger 111 during rotation of drum 23. As roller 110 contacts with cam 112, plunger 111 guided in bearings 114 and 115 of drum head 116, forcing plunger toward compression spring 117, releasing the pressure on levers 118 and 119 by moving wedge 120 from contact with lever at ends 121, thereby releasing the spring tension on clamping fingers. Simultaneously wedge surfaces 122 move so as to contact, slightly later, with clamping fingers 25 and 30, thereby opening a gap between fingers so as to permit the pipe to enter.

While the drum 23 is rotating to pick up pipes, the clamping fingers 25 and 30 are held open by 15 roller 110 attached to plunger 111 riding on straight surface 123 of cam 112.

The tubes having entered pockets 29, and drum continues to rotate, roller rides down cam surface 124, thereby moving plunger 111 so as to release 20 the clamping fingers, which contact with wedge shape surface 122 and simultaneously, but a trifle later, wedge shape surfaces 120 contact with corresponding wedge shape of levers 118, 119 at point 121 so that rivets 125 force clamping fingers 25 25 and 30 together in order to firmly hold the pipe in grooves 126 and 127 of clamping fingers 25 and 30.

It will be apparent from the foregoing description that by applying uniform pressure to both 30 clamping fingers 25 and 30, and because of the shape of the clamping fingers, the pipe will automatically be centered in relation to pocket 29, which center bears a definite relation to center of nozzle 92. Should there be no pipe in pocket 35 29, the movement of clamping fingers 25 and 30 will be limited by the surfaces 128-129 of clamping fingers 25 and 30 pressing against stem 130 of plunger 111, and the opening formed by the grooves 126 and 127 of clamping fingers 25 and 40 30 will be of sufficient size to allow the extended spray nozzle to pass through.

As the pipes are picked up to be enameled and the drum 23 rotates for this purpose, the roller 110 of plunger 111 rides up the incline 113 of cam 45 112, thereby opening the clamping fingers 25 and 30, and they remain open as long as roller 110 continues to ride along raised surface of cam, thus permitting the pipes to be picked up, rolled down projections 24 and 26, and shifted 50 by coming in contact with slanted projection 33 attached to head bracket 36 so that that end of pipes will be in a straight line, after which roller 110 rides down incline 124, permitting fingers to 55 clamp pipes. After the pipes have been enameled and the drum 23 again starts to rotate and discharge them, the action of the clamping fingers is merely reversed and the pipes discharged, as previously described.

Figs. 10 and 11 show in detail mounting of the 60 spray guns and automatic safety circuit breaking device and automatically operated check valve controlling functioning of fluid control mechanism of spray gun.

The spray guns are mounted so as to allow 65 lateral movement of same, which in turn will permit the attachment of means for automatically stopping the operation of the apparatus should for some reason any obstruction take place to prevent the nozzles of the spray guns from entering the pipe, as described following:

One or a number of spray guns may be mounted according to requirements. The bars 131 and 132 are attached to standards 133 and 75 provide bearings for the rods 134, which in turn

are held under tension by compression springs 135.

The shoulder 136 of rod 134 is pressed against bar 132. The spray guns are, by means of gun holders 137 which are guided in recesses 138 of bar 131, fastened to rod 134 with clamps 139.

In order to provide additional rigidity, the nozzle itself is held in a fixed position by clamp 140 to spray gun holders 137.

- 10 The above described mounting of the spray guns now allows the lateral movement of the gun above mentioned should nozzle strike any obstruction as carriage 38 with drum 23 attached start to move toward spray guns, in which event 15 the nozzle would be forced back, which in turn would move rod 134 against pivoted bar 141 to to which is attached right angle bracket 142. As bar 141 swings on pivots 143, bracket 142 contacts with lever 144 of electrical switch 145.
- 20 The electrical switch 145 being in circuit with driving means will tend to automatically stop functioning of the apparatus.

Figs. 1 and 2 illustrate at the extreme left-hand of apparatus, means for exhausting fumes 25 that may be created during the coating of the pipe on the inside. Hood 146 is attached directly to bracket 31 of carriage 38 and so located that ends of pipes to be coated extend inside of same.

30 Pipe 147 is attached directly to hood 146 and slides inside of pipe 148, which in turn is supported on bracket 149.

This construction provides a continuous exhaust connection as the carriage travels to and 35 from spray guns. At the end 150 of pipe 148 any suitable means may be connected for creating a suction to draw off fumes.

The operation of the apparatus in feeding, 40 coating and discharging the pipes is entirely automatic, and is quick in its action in that the entire operation occupies less than one minute, and the number of pipes per minute will depend upon the number of them held by the holder 23 for each operation.

45 In the specific embodiment shown three pipe sockets are indicated, but a larger or smaller number can be used, and in actual practice the handling of five pipes together in a group has proven advantageous, and results in a rate of 50 treatment that is made to easily correspond with other preceding treating apparatus and subsequent drying means for hardening the coating in place on the pipe surfaces.

This application is a continuation in part of 55 my co-pending application Serial No. 24,053 Apr. 18, 1925, which issued as Patent 1,789,596.

I claim:

1. In apparatus for treating pipes, the combination with means for holding a pipe, of means 60 for treating the pipe, means for producing relative movement between said holding and treating means, and means for automatically discontinuing said last named means upon a predetermined excess resistance to movement between 65 said holding and treating means.

2. In pipe treating apparatus, the combination with means for receiving said pipes and holding means, a feed for supplying said pipes 70 to treating means, of a drive for said holding means, a feed for supplying said pipes to said holding means, and means associated with said feed for automatically starting said drive by the movement of a pipe along said feed- ing means.

75 3. In apparatus for treating pipes, the com-

bination with treating means, of means for holding and moving the pipes with relation to said treating means and comprising movable members for engaging said pipes and automatically centering different sizes of pipes with relation to 80 said holding means comprising resilient means adapted to grip said pipes at a plurality of points.

4. In apparatus for treating pipes, the combination with treating means, of means for holding said pipes and producing relative movement between said pipes and said treating means, and comprising a drive having a chain means to reciprocate said holding means and rotary gears for intermittently rotating said holding means. 10

5. In apparatus for treating pipes, the combination with treating means, of means for holding said pipes and producing relative movement between said pipes and said treating means, and comprising a drive having a chain 20 means to reciprocate said holding means and rotary gears for intermittently rotating said holding means, said gears being driven by said chain means.

6. In apparatus for treating pipes substantially 25 long in proportion to their diameter, the combination with treating means, of a rotary carrier having elongated trough members adapted to receive and position said pipes with relation to said treating means, means for moving said 30 rotary member with relation to said treating means, and means for automatically timing said rotary member to first rotate it into position with relation to the treating means and then to move it longitudinally relative thereto throughout sub- 35 stantially the entire length of the pipes.

7. In apparatus for treating pipes substantially long in proportion to their diameter, the combination with treating means, of a rotary carrier having elongated trough members adapted to receive and position said pipes with relation to said 40 treating means, means for moving said rotary member with relation to said treating means, means for automatically timing said rotary member to first rotate it into position with relation to the treating means and then to move it longitudinally relative thereto throughout substantially the entire length of the pipes, and means for locking said moving means during rotation of said rotary member. 50

8. In apparatus for coating pipes, the combination with coating means for coating the interior surfaces of the pipes, of means for holding the pipes and producing relative movement between the pipes and coating means, exhaust 55 means for carrying away the fumes of said treatment at one end of said pipes, and means for automatically continuously positioning said exhaust means with relation to said pipes during the movement of said pipes under treatment. 60

9. In a pipe coating mechanism a plurality of spraying nozzles adapted to be inserted through the full lengths of corresponding pipes, a movable carriage for the pipes comprising supporting means adapted to position the pipes in alignment with said nozzles, a bracket mounted to move with said carriage and having openings aligned with said pipes and permanently supporting and alining said nozzles in relation to said tubes throughout the entire range of movement 70 of said carriage, and means for reciprocating said carriage to insert and withdraw said nozzles the full length of said tubes.

10. In a pipe coating mechanism a plurality of spraying nozzles adapted to be inserted through 75

the full lengths of corresponding pipes, a movable carriage for the pipes comprising supporting means adapted to position the pipes in alinement with said nozzles, a bracket mounted to 5 move with said carriage and having openings alined with said pipes and permanently supporting and alining said nozzles eccentrically in relation to the lower surfaces of the tube bores throughout the entire range of movement of said 10 carriage, and means for reciprocating said carriage to insert and withdraw said nozzles the full length of said tubes.

11. In a pipe coating mechanism a plurality of spraying nozzles adapted to be inserted through 15 the full lengths of corresponding pipes, a movable carriage for the pipes comprising supporting means adapted to position the pipes in alinement with said nozzles and grip said pipes at their end portions adjacent said nozzles, a bracket mounted 20 to move with said carriage and having openings alined with said pipes and permanently supporting and alining said nozzles in relation to said tubes throughout the entire range of movement of said carriage, and means for reciprocating 25 said carriage to insert and withdraw said nozzles the full length of said tubes.

12. In a pipe coating mechanism a plurality of spraying nozzles adapted to be inserted through the full lengths of corresponding pipes, a movable carriage for the pipes comprising supporting 30 means adapted to position the pipes in alinement with said nozzles with the center lines of the pipes above the center lines of the nozzles, a bracket mounted to move with said carriage and 35 having openings alined with said pipes and permanently supporting and alining said nozzles in relation to the lower surfaces of the tube bores throughout the entire range of movement of said

carriage, and means for reciprocating said carriage to insert and withdraw said nozzles the full length of said tubes while maintaining the upper surface of the nozzles spaced from the tube bore to provide continuous air spaces through 5 the upper portion of each of said tubes during the withdrawal movement of said nozzles, and means actuating said nozzles to cause them to project sprays toward one end of the tubes continuously during said withdrawal. 10

13. In a pipe coating mechanism for pipes substantially ten feet in length, a plurality of spraying nozzles adapted to be inserted through the full lengths of the corresponding pipes, a movable carriage for the pipes comprising supporting 15 means adapted to position the pipes in alinement with said nozzles, a fixed nozzle guide attached to said carriage and having guiding openings permanently fitted over said nozzles so that said spray nozzles are correspondingly longer than 20 said pipes.

14. In a pipe coating mechanism a plurality of spraying nozzles adapted to be inserted through the full lengths of corresponding pipes, a movable carriage for the pipes comprising supporting 25 means adapted to position the pipes in alinement with said nozzles, a bracket mounted to move with said carriage and having openings alined with said pipes and permanently supporting and alining said nozzles in relation to said tubes 30 throughout the entire range of movement of said carriage, means for reciprocating said carriage to insert and withdraw said nozzles the full length of said tubes, and exhaust means permanently connected to said carriage to move therewith and 35 remove the spray discharged from the ends of said pipes.

KURT T. POTTHOFF.

CERTIFICATE OF CORRECTION.

Patent No. 2,050,859.

August 11, 1936.

KURT T. POTTHOFF.

It is hereby certified that error appears in the printed specification of the above numbered patent requiring correction as follows: Page 5, first column, strike out lines 66 to 74 inclusive, comprising claim 2, and insert instead the following as claim 2:

2. In pipe treating apparatus, the combination with means for receiving said pipes and holding and moving them in predetermined relation to treating means, of a drive for said holding means, a feed for supplying said pipes to said holding means, and means associated with said feed for automatically starting said drive by the movement of a pipe along said feeding means.;

and that the said Letters Patent should be read with this correction thereon that the same may conform to the record of the case in the Patent Office.

Signed and sealed this 17th day of November, A. D. 1936.
